UNITED STATES PATENT OFFICE.

JAMES A. MUNDY, OF PHILADELPHIA, PENNSYLVANIA.

DESIGN FOR A PAVEMENT.

SPECIFICATION forming part of Design No. 18,708, dated October 30, 1888.

Application filed December 31, 1887. Serial No. 259,531. Term of patent 14 years.

To all whom it may concern:

Be it known that I, JAMES A. MUNDY, a citizen of the United States, residing in the city of Philadelphia, State of Pennsylvania, 5 have invented and produced a certain new and original Design for the Surface of Composite Pavements, of which the following is a full, clear, and exact description, reference being had to the accompanying drawings, forming a part of this specification.

My invention relates to composite pavements; and it consists of an ornamental design for the surface of such pavements.

By reference to the drawings, in which Figure 1 illustrates my design and Figs. 2, 3, and 4 show modifications thereof, it will be seen that the essential and distinguishing and novel feature consists of depressions A in the surface, arranged in parallel series or rows, those 15 in each row being connected together by parallel straight grooves B, passing from side to side of the depressions A, as in Fig. 1, or from

point to point thereof, as in Fig. 3. While these figures show the depressions opposite each other in the same row, they may be made 25 alternate, as at A' A', Fig. 2, without varying from the main feature as stated, and again may be additionally connected by cross-grooves D, as in Fig. 4.

What I claim is—

An ornamental design for the surface of composite pavements, consisting of a series of parallel rows of small figures depressed below the surface, said figures in each row being joined together by connecting parallel grooves, substantially as shown and described.

In testimony whereof I have hereunto affixed my signature this 19th day of December, A. D. 1887.

JAMES A. MUNDY.
